GEORGE J. ZISCH, OF NEWARK, NEW JERSEY, ASSIGNOR TO PETER A. SENA AND ROBERT A. EBERT, BOTH OF NEWARK, NEW JERSEY

PREPAYMENT METER FOR RADIO APPARATUS

Application filed January 18, 1929. Serial No. 333,257.

This invention relates to prepayment meters and more particularly to such as are applicable to control an electric current of the nature used in radio apparatus.

5 One object of the present invention is to provide a device which, upon the insertion of a coin or metal token, will complete an electric circuit thereby furnishing current to an electrically actuated apparatus for a 10 predetermined period of time.

A further feature is in the provision of means for utilizing a portion of the current to operate a motor geared to a train having a circuit breaker operable at definite intervals whereby the current is broken both to the 15 apparatus and motor.

Another purpose is to produce a device which will operate continuously without break if several coins be entered until the 20 last has been utilized.

These and other novel and practical purposes are attained by the construction and arrangement of parts hereinafter described and shown in the accompanying drawing, in 25 which:—

Figure 1 is a plan view of an embodiment of the device showing its main operative parts.

Figure 2 is a sectional view of line 2—2 of 30 Figure 1.

Figure 3 is a diagrammatical view of the electrical connections and wiring.

As shown, the device rests in a rectangular casing, generally designated by the numeral 35 10 in which is a raised platform 11 having mounted on it a small electric motor 12, its shaft 13 carrying a worm 14.

The worm 14 is meshed with a worm gear 15 fixed on a spindle 16 rotatable in a bracket 40 17 bolted to the platform 11, and on the spindle is a worm 18 meshed with a worm wheel 19 fixed on a spindle 20, parallel with the motor shaft, and rotatable in a bracket 21 bolted to the platform.

45 A stud 22, set in the side of the wheel 19, offset from its axis in the manner of a crank, has pivoted on it an arm 23 to which is pivoted, at 24, a bent lever 25 having at its opposite end a stud 26 in which is fixed a thin 50 spring contact arm 27.

Also rigidly secured to or formed with an offset elbow 28 of the lever 25, is a lever 29, having in its outer end a pin 30 to which is attached a tension spring 31, tending to draw the lever into a horizontal position and 55 also to take up any slack that may occur in the gear train and levers.

An upright plate 32 extends from the platform 11, parallel and adjacent the side of the casing opposite the motor, and set in the upper portion of this plate is an insulated 60 stud 33 carrying an adjustable contact screw 34 against which the end of the spring arm or contact element 27 rests when the device is in operation.

Secured to the inner side of the plate 32 is a downwardly inclined coin chute 35 having an entrance at 36 through the side of the casing and an insulated extension 37 at its inner end to guide a coin C so that when the coin 70 is eventually released it will pass through an opening 38 in the platform 11 to a coin receiving receptacle therebelow.

Intercepting the path of an entered coin, above the extension 37 is one horn 39 of a 75 crescent shaped escapement contact 40, the other horn 41 of which is so positioned as to prevent successive coins that may be placed in the chute from entering upon the extension 37 until after the coin thereon has performed 80 its full function and been released.

The contact element 40 is fixed on the inner end of the lever 29 and obviously moves in a gyratory path with it.

An electric current, from any convenient 85 source, enters the casing by the cable 42 passing upward through the platform where it is branched, one of the branches 43 being held by a binding screw 44 and the other branch 45 by the binding screw 46.

90 The branch 43 is connected to the lever carried pin 30 and the branch 45 is engaged with a plug socket 47 from which current may be taken for actuating a radio instrument.

A return conductor 48 from the plug socket 95 extends to the insulated screw 34, from which another conductor 49, leads to the insulated coin seat extension 37.

A shunt conductor 50 leads from the binding screw 46 to the motor 12 and thence by 100

a conductor 51 to join the conductor 48, as at 52.

If one or more coins be entered through the opening 36 to pass down the chute 35, the lowermost coin will make electrical contact with the horn 39, part of the escapement contact 40, through arm 29 to conductor 43 of the cable 42.

The coin rests upon the extension 37 thus forming a circuit through conductor 49, screw 34, conductor 48, through the socket 47, conductor 45 to the cable. At the same time part of the current is shunted to the conductors 50 and 51 energizing the motor 12.

If the motor speed is 2000 R. P. M. and the gear train reduction is 1000 to 1, by reason of the worms 14 and 18 being single pitch and the worm gears 15 and 19 each having 100 teeth, the crank stud 22 carried by the gear 19 will make one revolution in five minutes.

It is to be understood that the spring arm 27 is initially out of contact with the screw 34, but very soon after the motor has started and the gear 19 made approximately one tenth of a revolution, the arm 27 will engage the screw 34 and, as the arm 27 is in circuit with the conductor 43, by reason of its electrical connections with the stud 26 in the lever 25, thus conducting current through the socket 47 and motor 12 as before explained.

Meanwhile the horn 39 has moved to permit the coin to escape down the passage 38 and the horn 41 intercepts the next succeeding coin until substantially a full revolution of the wheel 19 has taken place, whereupon the next coin is admitted to rest upon the extension seat 37 and the cycle is renewed.

However, if there be no succeeding coin, revolution of the wheel 19 ceases at a point where the spring contact arm is slightly raised from the screw 34, thus interrupting the socket and motor circuit, causing cessation of further operations until another coin has been deposited.

As changes of construction could be made within the scope of the invention, it is intended that all matter contained in the foregoing description or shown in the accompanying drawings shall be interpreted as illustrative and not in a limiting sense.

Having thus described the invention, what is claimed as new and desired to secure by Letters Patent, is:—

1. A prepayment meter for electric dispensing devices comprising an electric motor, a reduction gear train driven by the motor, an escapement lever and a spring contact lever carried eccentrically by the last gear of the train, means operative upon the entrance of a coin to form an initial circuit through said escapement lever to start the motor and deliver current, and a terminal engaged by said spring contact lever to continue the electric circuit after the release of the coin until said last gear has made one full and complete revolution at

which time the spring contact lever will be removed from engagement with said terminal breaking the circuit.

2. In an electric current dispensing device, an electric motor, a reduction gear train including a crank wheel driven by the motor, two spaced contacts in the device each being connected with the same current, a spring arm actuated by the crank of said wheel to make and break the circuit to one of said contacts, an escapement also actuated by said crank, a starting element entrable the device to form a circuit between said escapement and the other of said contacts to initiate said motor, said escapement releasing the starting element when the spring arm has made electrical engagement with the first named contact, and means for delivering current outwardly the device during one full rotation of said crank wheel by the motor.

3. In an apparatus for vending a time limited electric current, a casing, an electric motor therein, an outlet socket in the casing, a meter gear driven by the motor, and a meter having means for making and breaking current connections to said motor and outlet socket upon the insertion of a circuit forming coin and a crank actuated spring drawn escapement to receive and convey the coin outwardly.

4. In an apparatus for vending a time limited electric current, a casing, an electric motor therein, an outlet socket in the casing, and a meter driven by the motor, said meter having a crank, insulated contacts in said casing connected to the motor and outlet, a spring arm carried by said crank to clear one of the contacts when the motor is at rest and to form a circuit therewith when the motor has begun operation, a rigid arm carried by the crank adjacent the other contact, means for guiding a coin to rest on the second contact in electrical engagement with said rigid arm to initially close the electric circuit to said motor and outlet, and means on said rigid arm to intercept successive coins until a preceding coin has been released from the last named contact.

5. In an electric current dispensing device, an electric motor having a main control switch, a rotary meter geared to the motor to revolve at a slow proportional speed relative thereto once in a certain time period, electric connections to said motor, other connections leading outwardly to dispense current, an escapement driven by said motor adapted to receive and discharge a starting means capable of forming a circuit between said connections and to said motor whereby the motor and meter are initially actuated only and the starting means discharged, and resilient means to normally draw said escapement into a position receptive of the starting means.

In testimony whereof I affix my signature.
GEORGE J. ZISCH.
